TELEVISION APPARATUS

Donald William Short, Woodridge, N. J., assignor,
by mesne assignments, to Radio Corporation of
America, a corporation of Delaware

Application April 16, 1932, Serial No. 605,580

3 Claims. (Cl. 178—6)

This invention relates to television transmission systems, and with particularity to an improved form of television pick-up unit for television transmitters.

5. An object of the invention is to provide an improved form of television pick-up camera having a monitoring unit attached thereto.

A feature of the invention resides in a television pick-up unit for a television transmitter 10 wherein the device that is used for scanning is also used for monitoring the image as it is being transmitted.

Another feature of the invention relates to a scanning device having two sets of scanning 15 units or elements arranged in reverse order.

Other features and advantages not specifically enumerated will be apparent after a consideration of the following detail descriptions and the appended claims.

20. While the invention will be described herein-after as embodied in one specific form of television transmitter pick-up, it will be understood that the invention is not limited thereto, but is to be utilized in any other known form of television transmitter.

Referring to the drawing,

Fig. 1 represents a side view in elevation of a television transmitter pick-up embodying features of the invention;

30. Fig. 2 is a front view of the device of Fig. 1; Fig. 3 is a detailed view of the scanning disc showing the arrangement of the two series of perforations therein; and

Fig. 4 is a schematic diagram of a portion of 35 the monitoring arrangement.

Referring more particularly to Figs. 1 and 2, the numeral 1 represents a stand capable of being moved readily to various positions, and for this purpose is preferably provided with rollers

40. 2. Mounted in the stand for vertical adjustment is a standard 3 which is capable of being locked in its vertically adjusted position by means of a suitable clamp 4. The standard 3 is rotatable about a vertical axis in the standard 5

45. which is carried by the stand 1, and a suitable locking member 6 is provided for locking the standard 3 in its adjusted position. The standard 3 carries a pair of U-shaped arms 7 and 8, these arms converging at their upper ends to

50. support trunnion bearings 9 in which is mounted the horizontal shaft 10. For the purpose of rotating the shaft 10 in its bearings, the said shaft carries a worm wheel 11 which cooperates with a corresponding worm 12 mounted for rotation on the bracket members 7 and 8. A suit-

able hand wheel 12 is provided for turning the worm and worm wheel to adjust the shaft 10. Shaft 10 has attached thereto a downwardly depending housing 13 in which is mounted any suitable form of motor (not shown) for driving the scanning disc 14. The shaft 10 also supports another housing 15 in which are located a photo-electric cell 16 and an amplifier 17. A box 18 containing a further amplifier and the necessary switches is attached to the platform 19 which carries the housing 15. The platform 19 has attached thereto a pair of brackets 20 in which is supported a suitable optical system 21 for imaging the subject or object to be televised, upon the scanning disc 14. It will be noted that the scanning disc 14 is attached to the motor shaft 22 so as to rotate in back of the optical system 21.

On the opposite side of the disc 14 from the optical system 21 is another optical system including a condensing lens 23 for projecting the scanned images upon the photo-electric cell 16. Attached to the left hand bracket 20 is an arm 24 in which is supported a television reproducing lamp 25 of known type, preferably one having a 75 flat plate luminous target, this target being indicated schematically in Fig. 3 by the numeral 26. The lamp 25 may be provided with a housing having an aperture therein as indicated schematically in Fig. 4, and as disclosed in detail in application Serial No. 453,890, filed May 20, 1930. The arm 24 is arranged so that the lamp 25 is in front of the disc 14. Positioned on the opposite side of the disc and in alignment with the lamp target is an eye piece or funnel shaped member 26 for viewing the lamp target through the disc openings.

It will be seen from the foregoing description that by rotating the handle 12 the entire television pick-up apparatus can be moved or rotated 85 as a unit about the shaft 10, thus preserving the fixed relation between the lens system 21, disc 14 and the cell 16, as well as the fixed relation between the lamp 25 and the disc 14. This construction therefore provides an assembly which is well adapted to pick up television scenes at different places or points since the entire unit is easily movable on the rollers 2, and it is easily 95 adjusted about horizontal and vertical axes while maintaining the proper relation between the optical elements of the system.

The manner in which the scanning disc 14 cooperates with the cell 16 to analyze the scene to be televised is in accordance with standard practice, and further description thereof is not believed 100 110

necessary. However, it is to be noted that the scanning disc 14 instead of being provided with a single spiral set of scanning elements is provided with a double set of these scanning elements as shown in Fig. 3. The outer spiral is utilized for scanning the scene or object to be televised while the inner spiral is used for monitoring purposes in conjunction with the lamp 25. Because of the fact that the object or scene is imaged by an ordinary lens system 21 upon the disc 24, the said image will be in a reverse up and down direction. Consequently in order that the image as monitored by the lamp 25 may be in its proper relation the inner or monitoring spiral 27 has a reverse lead from that of the outer spiral. Thus for example assuming that the disc of Fig. 3 is rotating in the direction of the arrow, then obviously the outer spiral 28 scans the image 29 from right to left. Consequently if the monitoring lamp 25 were on the same side of the disc as is the photo-cell 16 and this lamp were viewed through the disc from the front, the image as reproduced by the monitoring lamp 25 would be in the proper right-left position. It is obvious, however, that the person operating the camera or pick-up unit cannot be positioned in front of the disc since this would interfere with the scanning of the object. It is for this purpose that the lamp 25 is positioned in front of the disc and is viewed by the monitoring operator from the rear of the disc. However, in order to preserve the proper right-left direction of the monitored image the inner spiral 27 is in the reverse direction from the outer spiral 28.

On the other hand, inasmuch as the optical system 21 projects the image in a reverse up and down direction, the inner spiral 27 scans the image vertically in the opposite direction from the outer spiral 28, thus the image as reproduced by the monitoring lamp is in the proper up and down relation, and in the proper right-left direction so that the monitoring operator in looking through the disc 14 sees the image of the object exactly in the same relation as if he were looking directly at the object. The manner in which the lamp 25 is illuminated to reproduce the image is well known in television systems. Suffice it to say that the scene or object being scanned in successive elemental areas by the spiral 28 causes corresponding currents to be generated in the cell 16, which are amplified by the amplifier 17 and these amplified currents may be transmitted directly over wire or by means of radio to a distant station. A portion of this amplifier current is diverted to the lamp 25 so that the said lamp varies in brilliancy in accordance with the response of the photo-electric cell 16.

If desired the lamp 25 may be directly connected to the amplifier 17. In the event, however, that the televised signals are to be transmitted by radio, a small monitoring radio receiving set may be attached to the platform 10 and the output of

this radio set impressed upon the lamp 25, thus giving a double check on the pick-up and the radio transmission.

Inasmuch as the amplifying equipment and photo-electric pick-up unit is preferably in optical alignment with the system 21, it is necessary to mount the monitoring lamp 25 and the viewing device 26 to one side of this housing. Consequently the inner spiral 27 is designed so as to scan the monitoring lamp in spacial synchronism with the scanning of the outer spiral 28. In other words the first scanning element 30 of the outer spiral begins to scan the image 29 at the same time that the first scanning element 31 of the inner spiral scans the monitoring lamp. If desired of course the monitoring lamp may be positioned at any other part of the disc, for example it may be positioned diametrically opposite to the image 29 in which event of course the monitoring spiral 27 must be so arranged as to preserve the proper relation between its scanning and the scanning of the image by the outer spiral.

There is thus provided a unitary television pick-up camera which is readily adjustable to pick up images at different points and at the same time the operator is enabled to view the image as actually reproduced by television means, thus enabling a constant check to be made on the television pick-up as well as on the electrical transmission.

Various changes and modifications may be made herein without departing from the spirit and scope of the invention.

What is claimed is:

1. A television pick-up machine comprising a scanning disc having two separate series of scanning elements arranged in spiral sequence, each series extending substantially entirely around the disc, the elements of one series having an opposite pitch from the elements of the other series, a photo-electric cell cooperating with one series, and a monitoring image reproducing lamp cooperating with the other of said series.

2. A television pick-up machine comprising a scanning disc having two oppositely pitched spiral series of scanning perforations, each series extending substantially entirely around the disc, a photo-electric cell cooperating with one of said series, and an image reproducing monitoring lamp cooperating with the other of said series.

3. A television pick-up machine comprising a stand, a shaft mounted for rotation on said stand, a motor carried by said shaft, a television scanning disc attached to the motor shaft, a monitoring lamp supported by the first mentioned shaft in front of said disc, and a photo-electric cell supported by said shaft in the rear of said disc, said disc having two separate series of scanning elements arranged in spiral sequence, each series extending substantially entirely around the disc.

DONALD WILLIAM SHORT.
